UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

PERCUSSIVE DRILL UNIT

Application filed July 19, 1930. Serial No. 469,066.

This invention relates to percussive drill units, such as are used in conjunction with subaqueous drilling apparatus, and has particular reference to an improved means of connecting one part of the unit to another.

One object of the invention is to prevent unintended displacement of the drilling member forming part of the unit.

Another object of the invention is to insure the true alignment of the drilling member with the supporting portion of the unit.

Other objects will be in part obvious and in part pointed out hereinafter.

In the drawings, Figure 1 is a side elevation, partly in section, showing the drill and its support,

Figure 2 is a front elevation of the support with the drill removed,

Figure 3 is a section taken on the line 3—3 of Figure 1,

Figure 4 is a section taken on the line 4—4 of Figure 1, and

Figure 5 is a section taken on the line 5—5 of Figure 1.

Referring more particularly to the drawings wherein similar reference numerals designate corresponding parts throughout the several views, the drilling member forming part of the unit comprises a cylinder 10 which is provided at its rearward end with a back head 12 resiliently maintained in position by a heavy spring 14 abutting a flange 16 through which project bolts 18 entering the cylinder 10 and thereby holding these parts in position upon the cylinder.

The cylinder 10 is also provided with a piston chamber 20 in which reciprocates a piston 22 actuated by pressure fluid from a suitable source (not shown) flowing along the passages 24 and 26 in the wall of the cylinder 10. The pressure fluid may exhaust through a suitable port 28 in the cylinder and the flow of pressure fluid through the passages 24 and 26 may be controlled by any suitable type of valve, such as a slide valve, enclosed within the valve chest 30.

The piston 22 is, in this instance, formed with a reduced portion 32 extending from its front end for a short distance beyond the front end of the cylinder 10 and having guid-

ing means thereon in the form of a sleeve 34 which may be split to enable it to be assembled thereon. Enclosing the front end of the cylinder 10 and forming a support for the sleeve 34 is a front head 36. The front head 36 is preferably tapered on its outside surface and may also be split to facilitate assembly upon the sleeve 34. The sleeve 34 and front head 36 are preferably maintained in position by an internally tapered collar 38 having bolts 40 extending therethrough and threadedly engaging the cylinder 10. It will be apparent that the bolts may be adjusted to move the collar 38 along the tapered front head 36 to hold the parts together.

To prevent emission of pressure fluid from the front end of the cylinder, the front head 36 is provided with packing (not shown) maintained in position by any suitable means, such as a packing gland which, in this instance, comprises a collar 42 which may be split and have one end abutting the packing and the other end seated in a flange 43 which is secured to the front head by means of bolts 44.

Beyond the packing gland, the piston extension is preferably enlarged as at 46 and is threaded at its terminal end for engagement with a coupling 48 which also has provision for the reception of a hollow drill steel 50 by means of a thread 52 therein. Supporting this enlarged end 46 of the piston extension is a guide 54 in which the enlarged portion 46 is free to reciprocate. The guide 54 is preferably provided with annular flanges 55 which interlock on one side with a guide support 57 and on the other with a guide cap 59. Bolts 61^a extending through the guide support 57 and guide cap 59 may be used in conjunction with nuts 63 as shown in Figure 5 to secure these parts together.

In order to supply hole cleansing fluid to the end of the hollow drill steel 50 the enlarged portion 46 of the piston extension is provided with a passage 56 extending therethrough and terminating adjacent a plurality of ports 58 affording means of communication with the exterior of the enlarged portion. Convenient means are provided for the

admission of cleansing fluid to the ports 58 comprising a water head 60 fitting around the enlarged portion 46 of the piston extension and having a chamber 61 therein. An aperture 62 through the wall of the chamber 61 is preferably threaded for the reception of a pipe 64 which may convey the cleansing fluid from a suitable source (not shown) to the chamber 61, where it may enter the ports 58 and be conveyed by the passage 56 to the hollow drill steel. At either end of the water head 60 are recesses 66 into which there is inserted packing 68 maintained therein by means of the glands 70 and preventing the escape of fluid from the water head 60.

In order to enable the drilling member to be attached to the supporting portion of the unit and also maintained securely thereon, the cylinder 10, water head 60 and guide support 57 are provided with locating portions in the form of projecting lugs 72 and provision is made during the manufacture of these parts to so surface the faces 74 of the lugs that these faces will all lie in substantially the same plane upon assembly. The opposed edges 76 of the lugs 72 are also preferably surfaced to provide locating points to hold the drill against longitudinal displacement with respect to the supporting portion as will presently be apparent. Lateral displacement of the drill with respect to the supporting portion is also insured against by surfacing the edges 78 of the lugs 72 which lie normal to the edges 76 thereon as shown in Figures 3, 4 and 5.

The support for the drill, with which the lugs 72 may cooperate to maintain the drill securely in position against displacement, is, in this instance, in the form of a saddle member 80 of sufficient length to extend from a point adjacent the back head 12 to a point adjacent the coupling 48 on the piston extension. The saddle 80 is preferably provided with guiding surfaces 82 on one side in order that it may be reciprocated back and forth in the guideways of a winch (not shown) which forms another part of the apparatus used in connection with subaqueous or other drilling operations. A recess 84 is provided at one end of the saddle 80 for the reception of a pair of pulleys 86 which may rotate upon a pin 88 supported in the saddle 80. The pulleys 86 may have the usual grooves around their periphery to provide a guiding surface for the ropes 90 used to raise and lower the drilling mechanism.

The front surface of the saddle 80 is provided with projections 92 disposed at such points along its length that they will lie substantially opposite the lugs 72 on the cylinder 10, water head 60 and guide support 57 of the drill when these two members are assembled. The projections 92 are preferably raised above the surface of the saddle 80 in order that they may be surfaced in one

operation to provide contact faces all lying in the same plane for engagement with the aligned contact faces 74 on the drill. It will be evident therefore that when the contact faces of the projections 92 of the saddle and the contact faces 74 on the drill are in engagement, the drill will be maintained in true alignment with the saddle. To secure the drill in this position and against longitudinal movement the saddle 80 is also provided with laterally extending abutments or lugs 94 spaced along its length at such points that when the edges 96 thereon are surfaced there will be formed recesses of definite size between neighboring abutments into which the projecting lugs on the cylinder 10, water head 60 and guide support 57 will enter with the surfaced edges 76 on the latter elements insuring a close fitting contact with the edges 96 on the abutments 94. In this manner the drill will be held against unintended longitudinal movement with respect to the support.

Provision has also been made in this invention to insure against lateral displacement of the drill with respect to the support and to this end contact edges 98 are also provided on the projections 92 with which the surfaced edges 78 on lugs 72 of the cylinder 10, water head 60 and guide support 57 may contact. As stated in connection with the surfacing of the contact faces on the projections 92, the contact edges 98 on these projections may also be surfaced in a single operation, thus insuring the true vertical alignment of the drill with the saddle. The lugs 72 on the cylinder 10, water head 60 and guide support 57 and the projections 92 on the saddle 80, are preferably perforated for the reception of bolts 100 which in conjunction with nuts 102 may be used to secure the drill to the support.

From the foregoing it will be seen that location points have been provided along the length of the drill so that it may readily be retained securely in relationship to the support. Both longitudinal and lateral displacement of the drill with respect to the support have been eliminated and the true alignment of the drill thus insured at all times.

I claim:

A drill unit comprising a rock drill, a cylinder at one end of said rock drill, a guide support at the opposite end of the cylinder, a water head intermediate the cylinder and the guide support, spaced locating portions on the cylinder, the guide support and the water head having aligned contact surfaces, a saddle, transversely extending fixed lugs on the saddle interlocking with said locating portions to prevent longitudinal displacement of the drill, the guide support and the water head with respect to the saddle, longitudinally extending lugs on the saddle also interlocking with the locating portions to

prevent lateral displacement of the drill, the guide support and water head with respect to the saddle, said longitudinally extending lugs having aligned contact surfaces adapted
5 to engage the aligned contact surfaces on the drill to insure the true alignment of the drill with the saddle, and bolts extending through the locating portions on the drill, the guide support and water head and through the
10 saddle to secure them together.

In testimony whereof I have signed this specification.

CHARLES C. HANSEN.
